UNITED STATES PATENT OFFICE.

EDWARD M. WEEKS, OF WASHINGTON, DISTRICT OF COLUMBIA.

SAFETY BACKGROUND FOR CHECKS OR OTHER DOCUMENTS.

Application filed April 15, 1922. Serial No. 552,881.

To all whom it may concern:

Be it known that I, EDWARD M. WEEKS, a citizen of the United States, residing at Washington, in the District of Columbia, have invented certain new and useful Improvements in Safety Backgrounds for Checks or Other Documents; and I do hereby declare the following to be a full, clear, and exact description of the invention, such 10 as will enable others skilled in the art to which it appertains to make and use the same.

My invention relates to bills of exchange and commercial papers such as bank-checks, 15 drafts, notes and other negotiable instruments, also to bonds, stock certificates and all documents of an exacting character, wherein means for preventing or detecting alterations is desirable or important.

20 More particularly stated, this invention consists in the production of a safety base or background of paper, parchment or any other suitable material, adapted to be overprinted and overwritten, for uses such as aforesaid, and characterized by a safety tint, the latter produced by a multiplicity of relatively inconspicuous or subdued parallel stripes or lines, either waving in form or straight, of graduated width, printed, engraved or otherwise applied in two or more alternating blending and contrasting colors upon one or both sides of the paper as will hereinafter more fully appear.

25 In the accompanying drawings which form part of this application for Letters-Patent, and whereon like numerals indicate corresponding parts in the several illustrations:

Figure 1 is a top plan diagrammatic view 30 of my invention as applied to a strip of paper suitable for use as a bank-check by way of exemplification;

Figure 2 is also a diagrammatic view 35 showing a set of printing rolls as one means by which the surface configuration represented by Figure 1 may be produced;

40 Figures 3 and 4 are each relatively enlarged fragmentary views of complementary printing rolls suitably inked in colors for printing their respective portions of the completed product shown in Figure 1;

Figure 5 is also an enlarged fragmentary view showing part of a printing or offsetting roll to which has been transferred suitable color stripes in proper alinement and register from the rolls of Figures 3 and 4 respectively; and

55 Figure 6 is a fragmentary view in plan showing one of various repeat designs which may be substituted for the legend appearing in Figure 1.

60 Reference being had to the drawings and characters thereon, the numeral 10 indicates the body of a bank-check, which may be formed individually, or in pages as usual, with or without stubs, preparatory to being over-printed by the customary formal matter, and later filled in for use as a check or other document. The surface of body 10 is configured and tinted by a multiplicity of 65 individual, light parallel lines, which may be curved, straight, or of any conventional form, and continuous from side to side of the blank, but varying in color and may include a legend or design such as indicated by 70 Figures 1 and 6.

75 In practicing the present invention it is quite immaterial as to what contrasting colors are employed to produce the tinted background aforesaid, except that the colors should blend and should be repeated successively from end to end, or side to side, of the form. In the present illustrations by way of exemplification, the colors red, blue and green are indicated according to the 80 Patent Office Rules of Practice color chart.

85 In Figure 1 of the drawings the individual parallel colored lines aforesaid, forming the tinted background or safety base of a blank for bank checks and the like, are 90 of wavering form, they cross said blank from side to side, are of comparatively subdued intensity, and by a novel process are caused to produce in a contrasting flat color some inserted insignia such as the letters 95 E M W of Figure 1, or an emblem such as shown by Figure 6, repeated more or less throughout the entire blank.

100 The subdued background such as aforesaid is produced according to the present invention, by printing either from a flat press or a cylinder press, but preferably from the

latter represented diagrammatically by Figure 2 of the drawings, wherein the numerals 11 and 11', 12 and 12' represent inking rolls, 13 and 13' line reproducing rolls, and the 5 numeral 14 indicates the offsetting or final printing roll.

In the color scheme herein illustrated by way of exemplification, the said rolls 11 and 11' are red and blue inking rolls respectively, 10 of cylindrical form, each having the letters E M W as in Figure 1, or some other legend as in Figure 6 of the drawings, depressed therein to produce at suitable points non-inking areas.

15 In the present color scheme also, the complementary rolls 12 and 12' respectively, are provided with raised inking letters E M W as in Figure 1, or some other legend as in Figure 6, registering accurately with 20 the corresponding depressions aforesaid in the surfaces of rolls 11 and 11', for purposes which will later appear.

In direct contact with the inking rolls 11 and 12 is a reproducing roll 13, lined circumferentially and from end to end as indicated by Figure 3 of the drawings; while in like relation to the inking rolls 11' and 12' is a second reproducing roll 13' lined as indicated by Figure 4 of the drawings.

30 These rolls 13 and 13' are capable of printing or reproducing directly upon a check-blank or other surface, the desired safety base, but as indicated by Figure 2, they are preferably arranged and adapted 35 to bear directly upon a final offsetting or printing roll 14, to which, when properly inked, they impart in accurate alinement and register, the combined surfaces of Figures 3 and 4 as shown collectively by Figure 5, ready for the final imprint.

40 During this process, the line rolls 13 and 13' are inked from the red and blue rolls 11 and 11', respectively, except where met by the non-inking areas or voids of the said 45 inking rolls 11 and 11', these uninked portions being supplied however with green ink from the raised letters or other legend, of rolls 12 and 12', respectively, in the well understood manner of color printing.

50 Thus it will be observed in the present typical selection of colors, reading from left to right of enlarged Figure 5, that the parallel composite lines 15, whether upon the offsetting roll 14 or the finished product of 55 a safety tinted background 10, are of uniform width, but made up from the individual lines 15' and 15'' of Figures 3 and 4 respectively, in the following proportions, viz: 2/6 red and 4/6 blue; 1/6 red and 5/6 blue; solid blue; 1/6 red and 5/6 blue; 2/6 red and 4/6 blue; 3/6 red and 3/6 blue; 4/6 red and 2/6 blue, this latter and certain succeeding lines including also solid green color 16 in like proportions, and applied in 65 perfect register, from the green rolls 12 and

12' aforesaid, as a means of producing the inserted letters 16 of Figure 1, or other insignia 16' in a solid contrasting but subdued color. Continuing from left to right in the arrangement illustrated, the proportions shown are 5/6 red and 1/6 blue; solid red; 5/6 red and 1/6 blue; 4/6 red and 2/6 blue; 3/6 red and 3/6 blue; 2/6 red and 4/6 blue; 1/6 red and 5/6 blue; solid blue; 1/6 red and 5/6 blue; 2/6 red and 4/6 blue, and so on 70 throughout the entire blank.

Obviously the proportions and colors above indicated are merely one example of how the present invention may be carried out, it being entirely within the spirit of 80 this invention to vary both the number and variety of colors employed, as also the graduation thereof indefinitely, provided they combine to produce a relatively inconspicuous or subdued safety tint or background, made up of a multiplicity of individual and alternating stripes or lines of contrasting colors and graduated widths, so positioned and arranged as to blend one into the other at definite intervals from end to end, or side 90 to side, of the blank, and when desired to produce in addition a within contained insert of appropriate letters or other insignia, of a contrasting color or colors, but in exact 95 register with the lines 15, and made up by a continuation of said lines, or independent thereof.

Having thus described my invention, and one method by which it may be practiced, what I now claim and desire to secure by Letters-Patent is:

1. A safety base for bank checks and other documents characterized by a series of color bands successively blending into each other and produced by a multiplicity of independent parallel lines of graduated width.

2. A safety base for bank checks and other documents characterized by a series of color bands successively blending into each other and produced by a multiplicity of independent parallel lines of uniform width each formed by a plurality of contacting lines of graduated width.

3. A safety base for bank checks and other documents characterized by a series of color bands successively blending into each other produced by a multiplicity of independent parallel lines, and a legend insert formed by a continuation of the same lines in a contrasting color.

4. The method of producing a tinted safety background for bank checks and other documents which consists in so applying colored lines to such background as to produce a uniform variation of colors at definite repeated intervals.

5. The method of producing a tinted safety background for bank checks and other documents which consists in applying to said background a plurality of parallel lines of

graduated width and contrasting colors so as to produce a uniform variation of color at definite repeated intervals.

6. The method of producing a tinted safety background for bank checks and other documents which consists in so applying colored lines to such background as to produce a uniform variation of colors at definite re-

peated intervals and at the same time a legend insert in a contrasting flat color. 10

In testimony whereof I affix my signature, in presence of two subscribing witnesses.

EDWARD M. WEEKS.
